(57) **CLAIM**

The ornamental design for a faucet, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevational view of a faucet showing our new design;

FIG. 2 is a rear elevational view thereof;

FIG. 3 is a left side view thereof;

FIG. 4 is a right side view thereof;

FIG. 5 is a first perspective view thereof; and,

FIG. 6 is a second perspective view thereof.

The broken lines in the drawings illustrate portions of the faucet which form no part of the claimed design.
